(57) **CLAIM**

The ornamental design for remover for binding strips, as shown and described.

DESCRIPTION

FIG. 1 is a perspective view of a remover for binding strips showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dot dash dot lines immediately adjacent to the shaded areas represent bounds of the claimed design. The broken lines of the remover for binding strips are directed to unclaimed portions and form no part of the claimed design.
